UNITED STATES PATENT OFFICE.

ALBERT HELMBACH, OF SAARBRÜCKEN, GERMANY.

SHAVING-BRUSH.

No. 852,878.

Specification of Letters Patent.

Patented May 7, 1907.

Application filed May 29, 1905. Serial No. 262,934.

To all whom it may concern:

Be it known that I, ALBERT HELMBACH, a subject of the German Emperor and of the King of Prussia, and a resident of Saarbrücken, in the Province of Alsace-Lorraine and German Empire, dentist, have invented new and useful Improvements in Shaving-Brushes, of which the following is a specification.

10 In order to provide a shaving brush which is adapted to be sterilized, it is necessary that the brush consist of as few parts as possible and that said parts be assembled in such a manner that they may be readily separated and the tuft easily removed and replaced.

15 The object of the present invention is to provide a brush of this character, and this is accomplished by providing a holder or handle comprising a sectional, metal sleeve formed 20 of two parts, the longitudinal edges of which abut when in use, said sections being preferably connected by a hinge or link, and means for holding said sections together and in engagement with the brush tuft. In the embodiment of the invention illustrated, the members of said sectional sleeve are held together and in engagement with the tuft by an outer sleeve into which the sectional sleeve is adapted to be removably inserted. The 25 inner sleeve is provided at its end opposite the tuft with a bottom or laterally projecting plate, and by pressing on this bottom or plate said inner sleeve and the tuft engaged thereby may be forced from the outer sleeve. 30 When the inner sleeve is thus removed, the sections thereof may be readily separated to release the tuft.

35 In the accompanying drawings,—Figure 1 is a longitudinal sectional view of a shaving brush constructed in accordance with the present invention; Fig. 2 is a similar view of a slightly modified form; Fig. 3 illustrates another modification; and Fig. 4 is a detail of one manner of engaging the inner sectional sleeve of the holder with the tuft.

40 The brush includes a tuft *a* formed of any suitable vegetable or animal fiber arranged in such manner that it may be subjected to boiling, or sterilizing in hot water, without causing the fibers to separate or become detached. As shown, the tuft is composed of a series of fiber strands which are bent or folded upon themselves so that both ends thereof project or extend to the outer end of 45 the tuft, the several fibers being suitably con-

nected at or near the inner ends of the tuft. This tuft is carried by a holder or handle comprising two sleeves *b*, *c*, inserted one within the other, the inner sleeve *b* consisting of two parts which surround the inner end of 60 the tuft and clamp the same between them.

In the embodiment of the invention illustrated in Fig. 1, the space within the inner sleeve which is not filled by the end of the tuft is occupied by a plug *d*. The outer 65 sleeve *c* is provided at its end opposite the tuft with an inwardly extending rim, against which a plate *e*, closing the end of the inner sleeve, rests or bears. By exerting pressure on the plate *e* or plug *d* from the end of the 70 outer sleeve *c* opposite the tuft, the inner, sectional sleeve *b* is forced from the outer sleeve and the tuft *a* is readily detached therefrom.

The construction illustrated in Fig. 2 differs 75 from that shown in Fig. 1 by having a suitable ferrule *a'* at the inner end of the tuft, which ferrule is engaged by the correspondingly shaped end of the inner sleeve *b'*. In order to dispense with the plug *d* the bottom 80 plate *e'* is fixed to one of the sections of the inner sleeve *b'* and so shaped as to form a supporting surface for the other section of said sleeve. As the end of the tuft *a* or its ferrule 85 is, in this embodiment of the invention, firmly gripped by the inner sleeve *b'*, a plug *d*, which would interfere with the insertion of the tuft into the sleeve is not required.

The form of the invention shown in Fig. 3 90 differs from that illustrated in Fig. 2 by having the sections of the inner sleeve *b'* of different lengths. The shorter section of said inner sleeve is connected to the longer section by a link or hinge, and the longer section 95 is provided with a bottom plate *e''*. By this means, it is not necessary to force the inner sleeve *b'* entirely out of the sleeve *c* when it is desired to disengage or release the tuft from the handle, but it is only necessary to force out the inner sleeve to such an extent that 100 the shorter section thereof projects beyond the rim of the outer sleeve *c* when the tuft will be disengaged from the inner sleeve, the sections of said sleeve *b'* being, however, still connected by the aforesaid link or hinge.

105 In each of the forms of the invention illustrated, it is possible to release the tuft from the handle by pressure on the inner sleeve, that is to say, by forcing said sleeve out from 110 the rear of the holder.

The ferrule at the inner end of the tuft may have the form shown in Fig. 4, which differs slightly from that shown in Figs. 2 and 3. That is, in the form shown in Fig. 4, the ferrule a^2 is provided, in addition to the tuft engaging section corresponding to the ferrule a' of Fig. 2, with an extension or collar a^3 , and the inner sleeve b^3 of the holder will have a form corresponding to the ferrule and adapting it to securely engage the same.

Having thus described the invention, what is claimed is,—

1. In a shaving brush, the combination of a tuft, and a holder or handle consisting of an inner sectional sleeve engaging the inner end of the tuft, and an outer sleeve surrounding the sectional sleeve and constituting the outer portion of the handle and holding the sections of the sectional sleeve together and in engagement with the tuft said sleeves being adapted to be readily disconnected and engaged.
2. In a shaving brush, the combination of a tuft, a sleeve engaging the inner end of the tuft and consisting of two sections hinged together and having their longitudinal edges abutting, one of said sections being longer

than the other, and an outer sleeve adapted to receive said sectional sleeve.

3. In a shaving brush, the combination of a tuft, a sectional sleeve engaging the inner end of the tuft, and an outer sleeve surrounding said inner sleeve and having at one end an inwardly extending rim, against which the end of a section of the inner sleeve opposite the tuft is adapted to bear.

4. In a shaving brush, the combination of a tuft, a sleeve engaging the inner end of the tuft and consisting of two sections hinged together, one of said sections being shorter than the other, and the longer section having at its end opposite the tuft a laterally extending plate or disk, and an outer sleeve surrounding said sectional sleeve and holding the sections thereof in close engagement with the tuft.

In testimony whereof I have signed my name to this specification in presence of two subscribing witnesses.

ALBERT HEIMBACH.
